ELECTRONIC TIME-DELAY SYSTEM

Harry F. Mayer, Baldwinsville, N. Y., assignor to
General Electric Company, a corporation of
New York

Application February 28, 1951, Serial No. 213,171

2 Claims. (Cl. 250—27)

1

My invention relates to electronic time delay systems and, more particularly, to such systems as may be employed to delay a given electrical response for a specified time from the instant of actuation.

It is a primary object of my invention to provide an improved electronic time delay system to be used in connection with reduced voltage motor starting processes, automatically delayed application of anode voltage from the instant of energization of heater elements for certain types of vacuum tubes, and similar processes utilizing a time delay.

It is another object of my invention to provide an electronic time delay system which affords measured time delays of relatively long duration.

It is still another object of my invention to provide such a time delay system employing inexpensive and readily obtainable components.

In carrying out my invention, I provide an electronic circuit which, in effect, increases the time constant, (i. e., the product of resistance by capacitance) of a resistance-capacitance circuit by two separate operations acting together. A charged capacitor is thus made to discharge at a much lower rate than would be established for the given resistor-capacitor parameters and the slowly changing voltage across the capacitor is amplified and used when it reaches a predetermined magnitude to cause proper actuating current to flow through a load device such as a vacuum discharge device and a relay coil in series. Thus, the relay contacts are operated at some definite time after the condenser is started to discharge, such time being considerably delayed by the action of my circuit.

The features of my invention which I believe to be novel are set forth with particularity in the appended claims. My invention itself, however, together with further objects and advantages thereof, may best be understood by reference to the following description taken in connection with the accompanying drawing. In the drawing, Fig. 1 is a schematic circuit diagram illustrating a preferred embodiment of my invention; and Fig. 2 is a set of curves, drawn to a common time scale, illustrating the potential variation at two points in the circuit and also a capacitor discharge current variation during the operation of the invention.

Referring now to Fig. 1, I have shown a preferred circuit embodying my invention and including a source of alternating current and voltage 1 and source of positive and negative unidirectional potential, suitably represented by two rectifiers 2 and 3 together with two filtering capacitors 4 and 5 connected as a full wave rectifier to the source 1. For convenience, I have indicated that one side of source 1 is grounded, and have assumed for reference purposes that

2

grounded points remain at zero potential. Thus, the full wave rectifier establishes and maintains a positive unidirectional supply potential on conductor 6 and a negative unidirectional supply potential on conductor 7 when a switch 8, in series with source 1, is closed.

An electron discharge device, such as a vacuum tube triode 9, has its anode 10 connected to conductor 6 through a resistor 11 and its cathode 12 connected to ground. A second electron discharge device, such as a vacuum tube triode 13, has its anode 14 connected to conductor 6 and its cathode 15 connected to conductor 7 through two cathode resistors 16 and 17 in series. The junction point between resistors 16 and 17 is indicated as point 18 for convenience in the following explanation of circuit operation. The control electrode 19 of triode 9 is connected through a resistor 20 to point 18 and a second connection is made from the anode 10 through a timing capacitor 21 and a timing resistor 22 (which may be a variable resistor as shown) in series to point 18. Triode 13 and resistor 16 in series serve as a means for discharging the capacitor 21 with an effectively increased time constant; and triode 9 serves as a second means, operative during the middle portion of the discharging cycle, for further increasing the effective time constant and reducing the rate of decay of discharge current from capacitor 21.

The control electrode 23 of triode 13 is connected to the junction point between capacitor 21 and resistor 22 and also to the negative voltage supply conductor 7 through a switch 24. Another electron discharge device, shown by way of example as a screen grid thyratron 25, is connected serially from its anode 26 through a load device illustrated as the coil 27a of a relay 27 to the ungrounded side of source 1. To essentially eliminate chatter of relay 27, a capacitance 28 is connected in parallel with coil 27a. A control electrode 29 of thyratron 25 is connected through a current limiting resistor 30 to point 18, and the cathode 31 and screen grid electrode 32 are connected to the junction point of two biasing resistors 33 and 34 which are in series with the source 1.

Relay 27 is provided with two normally open contacts 27b and 27c adapted to be closed upon the energization of coil 27a. The contacts 27b and 27c are connected to some utilization circuit (not shown) which is to be completed after a specified time delay from the instant of actuation, which is the instant at which switch 24 is opened, as will be hereinafter explained.

The heater elements 35, 36, and 37 of the respective tubes 9, 13, and 25 may be supplied with power from a suitable step-down transformer 38 with its primary winding connected in series with source 1, as shown.

For an explanation of the operation of the circuit, assume that switch 8 is closed and that conductors 6 and 7 are maintained, by rectifiers 2 and 3, at respectively positive and negative unidirectional potentials with respect to ground. The heater elements of the various vacuum tubes are properly heated by power supplied from the energized transformer 38. Further, assume that switch 24 is initially closed so that control electrode 23 is at the negative potential of conductor 7. The cathode follower action of resistors 16 and 17 thus limits the anode current through triode 13 to a very small value, since a small amount of such current flowing drives cathode 15 positive in potential with respect to control electrode 23. The anode voltage across triode 13 is, therefore, slightly less than the voltage between conductors 6 and 7, and the potential at point 18 is highly negative, being almost the same potential as that of conductor 7. Since no current is flowing through resistors 20 and 30, control electrodes 19 and 29 are at the same negative potential as point 18 so that triode 19 and thyratron 25 are cut off from anode current flow therethrough. Coil 27a is thus de-energized and contacts 27b and 27c are in the open position. Capacitor 21 is charged to the full voltage between conductors 6 and 7 and was quickly charged to that voltage by transient current flow through resistance 11 and switch 24 after switch 8 is closed.

Now assume that actuation, i. e., the opening of switch 24, occurs at time $t=0$. Capacitor 21 is no longer maintained charged, and as it starts to discharge through the anode-cathode path of triode 13, the potential of electrode 23 approaches asymptotically the potential of point 18. However, the potential of point 18 does not remain fixed, for as the potential of electrode 23 rises, anode current through triode 13 increases and the potential of point 18 rises to only a slightly lesser degree than the potential of electrode 23, due to the increasing voltage drop across resistor 17. The discharge current, indicated by the arrow 4a in Fig. 1 flowing through resistor 11, triode 13, resistor 16, and resistor 22, produces a voltage drop across timing resistor 22 which holds the rise of potential at electrode 23 to a low rate. Thus, the discharge which makes the potential of control electrode 23 approach asymptotically the potential of point 18 is such that timing capacitor 21 is discharging toward a continually receding goal, with the result that the discharging process takes much longer than it would otherwise. In fact, the time constant of the discharge is multiplied approximately by the amplification factor of triode 13. The variation of potential at point 18 is illustrated by curve 39 in Fig. 2, and the first phase of operation just described occurs in the portion of the curve between time=0 and time= t_1 .

The potential variation at the anode 10 of triode 9 is illustrated by curve 40 in Fig. 2. During the first phase of operation, the decreasing charge on capacitance 21 causes the potential of anode 10 to drop very slightly, as shown in curve 40. The time variation of discharge current i_d is illustrated by curve 41 in Fig. 2. It will be seen that the capacitor 21 discharges in essentially a retarded exponential manner between the instants time=0 and time= t_1 . However, during the period between the instants time= t_1 and time= t_2 the discharge current i_d is sustained, i. e., its rate of exponential decay is lessened, and the potential at point 18 (curve 39) rises very slowly, as hereinafter explained.

Now at the instant when time= t_1 , the potential at point 18, and thus the potential of control electrode 19, becomes of such a value that anode current begins to flow and to increase slowly through triode 9, causing an increasing voltage drop across resistor 11 and driving the anode 10 and the positive side of capacitor 21 increasingly less positive in potential. The discharge current i_d is thus sustained and prevented from materially decreasing, but this, in turn, holds control electrode 23 at a negative potential with respect to cathode 15 so that the increase of current through resistor 17 and the positive growth of potential at point 18 is considerably retarded. This is the second phase of operation and occurs between time= t_1 and time= t_2 as shown in Fig. 2.

Expressed another way, the capacitance looking into capacitor 21 from the junction of capacitor 21 and resistor 22 is substantially equal to the capacitance of capacitor 21 multiplied by the control electrode to anode gain of triode 9. The equality would be exact if resistor 16 were short-circuited. The effective resistance looking into resistor 22 from the junction of capacitor 21 and resistor 22 is equal to the resistance of resistor 22 multiplied by the gain of triode 13 measured with the input between control grid and point 18, and the output between point 18 and conductor 7. Thus, the circuit as a whole between the instants time= t_1 and time= t_2 comprises a resistance-capacitance discharge circuit in which the actual time constant is effectively multiplied by the gain of triode 9 and again by the gain of triode 13.

When the potential at point 18 and at control electrode 19 becomes zero at time= t_2 , control electrode current starts to flow in triode 9. Thus, as the potential at point 18 continues to grow positively, the potential at control electrode 19 remains substantially constant, due to a voltage drop across resistor 20 caused by such control electrode current. The anode current through triode 9, therefore, remains substantially constant, i. e., the triode 9 ceases to produce any amplification with respect to potential variation at point 18, the potential at anode 10 remains substantially constant, and the discharge current i_d resumes a greater rate of decay, permitting a rapid rise of anode current through triode 13, because of the decreasing voltage drop across resistor 22, and a correspondingly rapid rise of potential at point 18. This is shown on curve 39 by the portion between time= t_2 and time= t_3 .

The potential at point 18, and thus the potential at the control electrode 23 of thyratron 25, reaches a given positive value at time= t_3 , such potential causing the thyratron 25 to conduct anode current, during positive half cycles of its anode voltage, sufficient to energize load device coil 27a and close contacts 27b and 27c.

Thus, a delay period equal to t_3 is interposed between the instant that switch 24 is opened and the instant at which the contacts 27b and 27c are closed.

After time t_3 , the anode current through triode 13 continues to increase slightly and then remains steady at some higher value. The thyratron 25 then continues to conduct anode current, on its positive half cycle of anode voltage, so that contacts 27b and 27c remain closed. When switch 24 is again closed, the current through triode 13 decreases to a very small value, capacitance 21 charges up to its original voltage, tubes 9 and 25 are cut off, contacts 27b and 27c open, and the circuit is ready to repeat the actions hereinbefore described.

The self-biasing resistor 16 is not essential to the circuit, but its use is desirable because it prevents control electrode current from flowing in triode 13 as the end of the discharge of capacitance 21 is approached. Any such control electrode current makes the effective resistance of resistor 22 smaller and reduces the biasing action of discharge current i_d .

The rectifiers 2 and 3 shown in Fig. 1 may be of the hot or cold vacuum diode type, if desired, or of the copper oxide or selenium type. If rectifiers requiring no cathode heating time are used, however, the use of switch 24 is optional, since the closing of switch 8 may then constitute timing circuit actuation. That is, with switch 24 removed from the circuit or permanently opened, the rectifiers instantly apply unidirectional potentials to conductors 6 and 7 when switch 8 is closed. The capacitor 21 charges up to full voltage very quickly through resistors 11, 22, and 17 before the heater elements of the various vacuum discharge devices become hot enough to permit anode current flow; and when the heater elements do reach the proper temperature for anode current flow the operation of the circuit proceeds as hereinbefore described from the instant that switch 24 is opened. Circuit actuation by this method, therefore, extends the time delays obtainable by the length of time necessary to heat the heater elements and cathodes sufficiently for electron emission therefrom.

My invention is not limited to the use of a thyratron for the tube 25 but obviously includes the use of other vacuum discharge devices. Such devices may easily be connected, if desired, to the positive potential conductor 6 to supply them with unidirectional anode voltage instead of being connected across source 1 to receive an alternating anode voltage supply. Further, my invention obviously includes the use of relay contacts or other circuit-completing means in place of the manually operated switches 8 and 24.

My electronic time delay system has been built and tested and found to operate as hereinabove described. Merely by way of illustration and in no sense by way of limitation, I have found that the following circuit constants may be employed for the elements of the circuit:

Source 1	115 volts, 400 cycles per sec.
Rectifiers 2 and 3	selenium diodes
Capacitors 4 and 5	0.10 microfarad
Triode 9	one-half of a type 12AX7 duplex triode
Resistor 11	1.0 megohm
Triode 13	one-half of a type 12AX7 duplex triode
Resistor 16	15,000 ohms
Resistor 17	1.0 megohm
Resistor 20	1.0 megohm
Capacitor 21	0.25 microfarad
Resistor 22	5.1 megohms (variable)
Thyratron 25	type 2D21 thyratron
Relay coil 27a	6500 ohms; 10 m. a.
Resistor 30	1.0 megohm
Resistor 33	39,000 ohms
Resistor 34	4,300 ohms
Transformer 38	115/6.3 volts @ 400 cycles per sec.

The time delay obtainable using the above circuit constants was found to be adjustable over a range from approximately zero to 4.5 minutes by varying the value of resistor 22. It was further found that considerable adjustment of

the duration of time delay could be obtained by making resistor 16 variable and adjusting its resistance to various values.

While I have shown and described a preferred embodiment of my invention, other embodiments and modifications will occur to those skilled in the art, and I intend to cover in the appended claims all such modifications as fall within the true spirit and scope of my invention.

What I claim as new and desire to secure by Letters Patent of the United States is:

1. An electronic time delay system comprising a timing capacitor and a timing resistor in series; a first source of positive unidirectional operating potential and a second source of negative unidirectional operating potential; means for discharging said timing capacitor with an effectively increased time constant comprising a first resistor and a first electron discharge device having a first anode, a first cathode, and a first control electrode; said first resistor connecting said first cathode and said second source, said first anode being connected to said first source, said first control electrode being connected to the junction point of said timing capacitor and said timing resistor, and said first cathode also being connected to the terminal of said timing resistor remote from said junction; means operative only during a middle portion of the discharge of said timing capacitor comprising a second resistor, a third resistor, and a second electron discharge device having a second anode, a second cathode and a second control electrode; said second resistor connecting said second anode and said first source, said third resistor connecting said second control electrode and said first cathode, said second anode being also connected to the terminal of said timing capacitor remote from said junction, and said second cathode being connected to a point of zero potential; a third electron discharge device having a control electrode circuit and an anode circuit; a load device connected in said anode circuit; and means for biasing said control electrode circuit in response to the voltage across said second source and said first resistor in series; the anode current in said third device being insufficient to energize said load device until the voltage across said first resistor rises to a predetermined value.

2. An electronic time delay system comprising a first electron discharge device having a first anode, a first cathode, and a first control electrode; a first source of positive unidirectional operating potential connected to said first anode; a second source of negative unidirectional operating potential; a first resistor and a second resistor connected in series relationship between said first cathode and said second source, said first resistor being connected to said second source; a second electron discharge device having a second anode, a second cathode, and a second control electrode; said second cathode connected to a point of zero potential; a third resistor connecting said second anode and said first source; a timing capacitor and a timing resistor serially connected between said second anode and the junction of said first and said second resistors; said first control electrode being connected to the junction of said timing capacitor and said timing resistor; a fourth resistor connected between said second control electrode and the junction point of said first and said second resistors; means removably connecting said first
